UNITED STATES PATENT OFFICE.

PIETRO CANE, OF BROOKLYN, NEW YORK.

STRETCHER FOR EMBROIDERING.

Application filed October 7, 1922. Serial No. 592,960.

To all whom it may concern:

Be it known that I, PIETRO CANE, a citizen of the United States, and resident of New York city, borough of Brooklyn, in 5 the county of Kings and State of New York, have invented certain new and useful Improvements in Stretchers for Embroidering, of which the following is a specification.

10 This invention refers to improvements in implements for needlework, and especially it applies to frames used for stretching woven fabric to be embroidered.

To judge by the present state of the art, 15 as it appears from common usage, there has been very little improvement attained from the common single embroidery frame, consisting of a quadrangular non-adjustable wooden border or annular hoop 20 on which the fabric is stretched and fastened by pins or nails or any primitive manner to the more modern double chase or tambour frame, either one of which consists of a pair of concentric frames, the first 25 kind of rectangular or square shape, the other of annular form. In either case these two frames closely fit one into the other, so that, when a piece of cloth is spread over the inner or narrower frame, the outer 30 frame can be pressed over it until it lies flush with the inner one, stretching the cloth, while being forced over, so that it presents a tightly drawn, drum-like surface on which then the embroidering may 35 proceed. The main drawbacks of this class of frames consist in the distortion to which in practise design the fabric is subjected, and which is beyond the control of the operator, not to mention the facility with 40 which these frames separate, even before such parting is intended or desirable, and the consequent impossibility to remount the fabric on the frame with exactly the same strain in every direction as before.

45 It is also known to the inventor that the principle of the adjustable stretcher frame, consisting in the application of four sticks with slotted or perforated ends joined together by removable clamps or pegs into a 50 rectangle, on whose sides the fabric is fas-

tened by pins or nails, is old, and is, for example, utilized in the stretchers on which washed curtains are dried, but its unmodified application for the purpose of embroidery is also subject to similar criticism 55 and that of uneven straining of the fabric.

The first object of this invention is to devise an apparatus for stretching fabric for embroidery purposes, which is entirely controllable by the hand of the operator. 60 Another purpose is to distribute the strain evenly upon the warp and woof of the fabric without any distortion in a diagonal direction, in which the so-called "bias" runs.

A third purpose is to avoid such distortion 65 of the fabric as results from joining the fabric and stretching it at the same time, by a device which separates these two operations.

A fourth object is to provide a stretching frame which permits the even and complete mounting and stretching of irregular or odd pieces, irrespective of their size.

A fifth object, collateral with the last mentioned, is to devise an embroidery frame 75 in which the fabric to be operated upon does not have to be fastened to the rigid border of the frame.

Other and minor objects will become evident from the description.

These various objects are attained by the mechanism and arrangement of parts shown in the accompanying drawing, in which—

Fig. 1 shows a rear view of the embroidery frame, before the work piece is 85 attached to it;

Fig. 2 shows the front or working side of the frame, with the work piece attached to it, in an expanded condition;

Fig. 3 is a sectional view through one 90 of the press buttons by which the segments of the back canvas are held together;

Fig. 4 is an enlarged sectional view taken on line 4, 4 of Fig. 2 and illustrating the details of one of the corner clamps.

The same numerals refer to identical parts throughout the different views.

The rigid part of the frame consists of two pairs of beams or sticks of rectangular section, preferably made of wood, one pair 100

laid across the other pair, in such way that the ends of one pair are superimposed upon those of the other pair, the ends at each corner overlapping the other beam, so that 5 the combination form a rectangular frame, as the beams 1, 3 and 2, 4 in Fig. 1 show. Whether these beams should all be of equal length and thus be best adapted to form a square, as in the case illustrated, or whether 10 they should be of two different lengths, thus forming an oblong rectangle, depends upon the special requirements of the work to be done. In the majority of cases, an equilateral frame will be found most advan-

15 tageous.

The ends of the beams are slotted for a convenient length, as indicated by the slots 1^m, 1^p; 2^p, 2^t; 3^t 3ⁿ and 4ⁿ 4^m, so that 20 threaded bolts *m*, *n*, *p* and *t* can be inserted through the superimposed slots and, when a thumb nut is applied to their threaded end and drawn tight they will clamp the two beam ends securely together. Fig. 4 shows 25 one of these corner clamps in more detailed form. Underneath the head of the bolt, in this case bolt *m*, which connects the beams 1 and 4, respectively their slotted portions 1^m and 4^m, as well as under the thumb nut *m'* washers *m''* are inserted for distributing 30 the pressure exerted over a larger area of the beams.

It is evident that this arrangement, which is that of the adjustable stretcher frame, spoken of, allows to form rectangular 35 frames of varying lateral sizes, according to the available length of the slots.

On this border frame a canvas backing or cloth of suitable fabric is fastened, which is cut up into a plurality of segments along 40 the middle lines and the diagonals of the rectangle formed by the frame. This division, it will be seen from the illustration, results in four equal symmetrical pairs of 45 triangular pieces all of the same area and size, each adjoining pair symmetrical on its dividing line and congruent when folded over this line. See 1^a, 1^b; 2^a, 2^b; 3^a, 3^b; and 4^a, 4^b. The sides of each triangle are formed 50 respectively by half of one frame beam, half a diagonal and half of one middle line. The side adjoining the frame is permanently 55 fastened by nails, tacks or otherwise upon that side of the frame-beam which rests upon or faces the cross beams. See 1^d, 3^d in Fig. 1 and 2^d, 4^d in Fig. 2.

The diagonal sides which in each case are marked by the addition of symbols *f* or *f'*, as well as the sides adjoining the middle lines, characterized by the symbols *e* and *e'*, 60 added to the respective numerals designating the sides, are hemmed and, when the frame is in its original or unstretched condition, just butt against each other, or leave no substantial clearance between them. 65 They all converge towards the center 6 of

the frame and at this point a small lap 5, which may be square or round, is provided which covers the pointed loose ends of all the segments. Arranged in annular series 70 between the lap and the segment ends around the common center is a row of snap or press buttons 1^c, 2^c, 3^c and 4^c fastened with their sockets *c''* and button members *c'* (Fig. 3) to the segments and the lap respectively, so that when the lap is spread 75 fittingly over the loose corners, by a gentle pressure all the loose ends can be tied together with the lap into a continuous sheet.

Only one segment, for example 1^a, is permanently fastened to the lap, as indicated by the seams 5^a, and in this case the press button is dispensed with. This prevents the accidental loss of the lap and at the same 80 time insures the proper placement of the lap over the other segments, so that the fitting and buttoning is facilitated. Moreover, the slots 1^m, 4^m; 1^p, 2^p; 2^t, 3^t and 3ⁿ, 4ⁿ are of just such depth, that when the four beams 85 are shoved together, so that the bolts *m*, *p*, *t* and *n* are pushed inward, as far as they will go, the segments are drawn to such a close 90 that the press buttons are just in a position for ready snapping.

The operation and proper use of this 95 frame is presently explained.

After all the segments are buttoned tight to the center lap, as just described, the frame is turned over so that the lap is on the under side, and the piece to be embroidered, indicated by 7, is laid out flat and unstretched upon the canvas or back cloth, taking care that the warp and the woof of the fabric runs parallel to the frame beams. The bias threads, if there are any, will run diagonally.

In this position the working piece is either pinned to the backing or hemstitched or basted to it, as indicated by seams 8.

Then the lap on the back is unbuttoned, so that the loose ends of the different segments can flap downwards, as far as the basting does not hold them in the plane of the frame, if the latter is lifted from the table or other support. This is indicated by dotted lines 9, and the piece to be embroidered is thereby laid bare and free on both sides. Now, with all four corner clamp bolts loosened, the frame is spread apart in the direction of the middle lines, as far as the 100 fabric, basted to the loose segments, will permit without overstraining, tightening and loosening the corner bolts alternately, until the working piece lies evenly taut and without showing any crease or slack in either direction. Then the bolts are clamped permanently tight in their slots, and the working piece is ready to be embroidered.

As Fig. 2 indicates, the segments, in stretching, separate in diagonal directions,

that is, the hems 2^t, 3^t; 3^t, 4^t; 4^t, 1^t and 1^t, 2^t spread apart, parallel to each other, while the hems on the middle lines, marked with the symbols *e* and *e'*, only slightly spread toward the center. This peculiar action is due to the permanent fastening of the segments to the side beams in combination with the intentional splitting of the back cloth on the lines indicated and has 10 a peculiar effect on the stretching of the fabric.

In any rectangle of the sides A and B, the diagonal C equals

$$15 \sqrt{A^2 + B^2}$$

and in a square of the side A the diagonal C equals

$$\sqrt{2} \times A.$$

20 Consequently it can easily be proven, that when a square is expanded in both a longitudinal and lateral direction, viz: in such manner that the resulting shape always stays a square, the strain or elongation in all 25 diagonal directions must be equal to the strain exerted parallel to the sides times $\sqrt{2}$, that is; about 1.414 times as great.

As a corollary it follows that when a square is expanded by a force which would 30 act from the center outwardly, with even pressure in all radial directions, the square will bulge out on the sides and tend to approximate a circular circumference.

The first condition is that which happens 35 when a continuous loose sheet is stretched over a square frame, drawing it evenly in two directions, parallel to the sides and normal to each other. We will furthermore assume that the woof and warp threads 40 run also in these directions and are to be kept as nearly straight as possible. This results in excessive strain in a diagonal direction which has to be taken up by the bias threads and partly also by the woof 45 and warp threads, interwoven and coherent with them. In other words, the strain on the cloth increases towards the corners.

The other condition would be ideal for 50 the treatment and durability of the fabric, but would necessitate a distortion of the design to be embroidered.

It is therefore necessary in practise to 55 compromise between the two extremes, and this is done by the peculiar construction of the present device. The parting of the canvas backing along the diagonals alleviates the strain on the bias and consequently distributes the total strain on the fabric more evenly. A further consequence 60 is that there is very little distortion of the design, especially towards the middle and that the woof and warp threads are kept respectively almost parallel to each other. It is understood that the underlying principles of the invention will allow various

modification of execution in practise and that the description given is illustrative rather than restrictive.

Having thus described my invention, what I claim as new and desire to protect by Letters Patent, is:

1. In a frame for embroidering, the combination with a pair of stretcher beams and means to adjustably and fixedly hold them in parallel opposition; of two members, made of pliable material and fastened respectively at their outer portions to said stretcher beams and extending triangularly within the frame, said members at their inner portions extending freely within the space bounded by said beams, and means to temporarily connect the inner portions of said members to each other to permit said members to be stretched while connected at their inner portions when a piece of fabric is being attached thereto.

2. In a frame for embroidering, the combination with two pairs of stretcher beams, arranged normally to each other and means to adjustably connect them at their ends; of a backing sheet supported and expanded between said stretcher beams, and comprising segment portions having outer edges located along diagonal lines within the space bounded by said beams to hold a piece of fabric between them in suspension, said edges of portions diagonally disposed within the frame coinciding, said edges being arranged to separate in directions transverse to said diagonal lines to stretch said fabric and leave said portions free at their ends opposing the piece of fabric.

3. In a frame for embroidering, the combination with two pairs of stretcher beams, arranged at an angle to each other and means to adjustably connect them together; of a backing sheet comprising triangular portions, a pair of triangular portions having their bases attached to each of said beams and having their apices adapted to 105 adjoin within the space between said beams, the outer edges of said portions being disposed substantially diagonally to said frame, the diagonal edges of adjacent portions opposing one another to part in directions 110 transverse to such diagonals when the beams are adjusted laterally.

4. A frame for embroidering as specified in claim 3 provided with a lap to connect the apices of said portions, and means to 115 detachably connect said lap to some of said portions.

5. In a frame for embroidering, the combination with two pairs of stretcher beams, arranged at an angle to each other and means to adjustably connect them at their ends; of a backing sheet comprising a plurality of triangular portions, a pair of triangular portions having their bases attached to each of said beams, said portions 125

having inner adjacent edges substantially normal to the corresponding beam and having outer adjacent edges substantially diagonal to the frame, the diagonal edge of a portion on one beam opposing the diagonal edge of an adjacent portion on an adjacent beam, the apices of said triangular portions extending freely within the frame toward its mid-portion, in proximity to one an-

other, said portions being adapted to separate on lines normal and diagonal to said frame when the beams are adjusted laterally.

6. A frame for embroidering as specified in claim 5 provided with a lap to connect the apices of portions, and means to detachably connect said lap to some of said portions.

PIETRO CANE.
